UNITED STATES PATENT OFFICE.

WALTER T. GODDARD, OF ROCHESTER, NEW YORK, ASSIGNOR, BY MESNE ASSIGNMENTS, TO LOCKE INSULATOR CORPORATION, OF BALTIMORE, MARYLAND, A CORPORATION OF MARYLAND.

INSULATOR.

1,426,981. Specification of Letters Patent. Patented Aug. 22, 1922.

Application filed July 5, 1919, Serial No. 308,810. Renewed November 7, 1921. Serial No. 513,555.

To all whom it may concern:

Be it known that I, WALTER T. GODDARD, of Rochester, county of Monroe, and State of New York, have invented certain new and useful Improvements in Insulators; and I do hereby declare the following to be a full, clear, and exact description of the same, reference being had to the accompanying drawings, forming a part of this specification, and to the reference numerals marked thereon.

My present invention relates to electrical apparatus and more particularly to insulators of the type adapted to withstand considerable strain and involving one or more units each comprising, as a rule, a frangible refractory element possessing the insulating properties and a connected element of metal by means of which the units are attached to each other or to a support or to the thing supported and the invention has for its object to provide an improved means for connecting the said elements together in a manner both electrically sound and mechanically efficient, the principal aim being to distribute the attaching strain so uniformly through the mass of the weaker of the two elements, namely, the refractory insulating material that the apparatus as a whole will be able to withstand larger strains than hitherto. Further objects of the invention are to provide an insulator that can be economically produced and that will offer certain advantages in the way of setting up or assembling. To these and other ends the invention resides in certain improvements and combinations of parts all as will be herein-after more fully described, the novel features being pointed out in the claims at the end of the specification.

In the drawings:

Figure 1 is a side view of a single insulator unit constructed in accordance with and illustrating one embodiment of my invention;

Figure 2 is an enlarged fragmentary vertical section through one end thereof, and

Figure 3 is a top view.

Similar reference numerals throughout the several views indicate the same parts.

Features of my invention are applicable to both suspension and pin type insulators, but I have, in the present instance, shown

the invention embodied in a suspension insulator comprising generally connecting elements A and B at the respective ends of an intermediate vertically disposed insulator body C, the said connecting elements furnishing means above and below for attachment to the support and the thing supported whether these be other units of a series or otherwise. The body portion C is in the form of an elongated mass of the usual frangible refractory silicious material provided with a succession of skirts 1 and otherwise designed to produce the longest possible arcing distance between points of conductivity or possible conductivity. Headed portions 2 at the ends of the body C have arcing rings 3 clamped about them in proper spaced relationship by means of bands 4 drawn together by bolts 5. As clearly shown in Figure 3, half of the ring and half of the band are made in one piece in each instance.

As each end of the insulator body C is fitted with the same kind of a connecting element, a description of one will suffice for both. I provide the head 2 with a plurality of lateral openings 6 equally spaced from each other and disposed successively in staggered relationship around the periphery. Intersecting each such opening is a vertical opening 7 proceeding downwardly from the top or end face of the head. These openings are flared at the entrance thereto in each instance to facilitate the insertion of the connecting links hereinafter described and they constitute eyes at a number of different points to which attachment is made and where supporting strains are applied so that such strain points may be numerous and the strains uniformly distributed through the mass of refractory material and its resistance to fracture thereby greatly increased.

Overlying the head 2 is a steel disc or plate 8 formed with a boss 9 at its center which is struck up to provide a socket 10 on the under or inner side of the plate and received in this socket is the enlarged end or button 11 of an eye 12, the shank 13 of which passes through an enlarged central opening 14 in the boss to give not only a swivelling but a universal tilting freedom to the eye 12 in the manner of a ball and socket joint. Because of this, strains applied to the insu-

lator laterally or angularly through the medium of the eye 12 are redirected axially of the refractory mass.

Of course, it is necessary not only that the 5 points of the application of strain to the frangible body C be uniformly distributed through the mass, but that the strains be proportionately divided among them as far as possible. To this end, I suspend the body 10 C from the plate 8 or the plate 8 from the body C, as may be the case, by means of a plurality of inextensible links 15 preferably in the form of U bolts passing through the eyes 6 and the insertion of which, in the 15 first instance, is facilitated by the previously described flaring of the eye openings. These bolts pass through openings 16 in the plate 8 and thence through rockers 17 one of which is provided for each bolt to give it an individual bearing upon the opposite side of the 20 plate, the single bearing point of each rocker being indicated at 18. These act as equalizers to symmetrically suspend the refractory body from the bolt and the latter is in each case allowed a fair amount of slippage 25 in its eye so that it may adjust itself to the direction of strain and absorb its proportion. The nuts 19, through the medium of which the strain on the bolts is communicated to 30 the rocker are tightened uniformly around the disc in succession until the rockers are all level and each bolt is in contact with its respective eye. With the universally movable eye 12, the rocking pressure at 18 at 35 many points and the slippage of each U bolt in its eye, there will then be no harsh strain localized at any particular point and the resisting power of the insulator as a whole to fracture will be greatly increased.

40 I claim as my invention:

1. In a strain insulator, the combination with a frangible refractory element of silicious material and a connecting element, one of said elements being supported by the 45 other to resist strains, said refractory element being provided with a plurality of eyes, of independent link members extending through the eyes and each having a rocking bearing on the connecting element.

50 2. In a strain insulator, the combination with a frangible refractory element of sili-

cious material and a connecting element, one of said elements being supported by the other to resist strains, said refractory element being provided with a plurality of 55 eyes, of inextensible links extending through the eyes and each having an independent rocking bearing on the face of the connecting element away from said refractory element. 60

3. In a strain insulator, the combination with a frangible refractory element of silicious material having a plurality of passages therein and a connecting element, one of said elements being supported by the other to resist strains, of a plurality of link members 65 for connecting said elements, each of said link members being respectively adapted to extend through one of said passages, the said passages being so located as to distribute 70 strains uniformly throughout the mass of said refractory element, each of said link members also having an independent rocking bearing on said connecting element.

4. In a strain insulator, the combination 75 with a frangible refractory element of silicious material having a plurality of passages therein and a connecting element, one of said elements being supported by the other to resist strains, of a plurality of U-bolts for connecting said elements, each of said U-bolts being respectively adapted to extend through 80 one of said passages, the said passages being so located as to distribute strains uniformly throughout the mass of said refractory element, each of said U-bolts having the free 85 ends thereof connected by a rocker, said rockers having a bearing on the said connecting element.

5. In a strain insulator, the combination 90 with a frangible refractory element of silicious material having an annular attaching portion provided with a plurality of eyes disposed in staggered succession and equally spaced about the periphery thereof, and a 95 connecting element, of a plurality of independent inextensible link members extending freely through and engaged in the respective eyes and each having a rocking bearing on the connecting element.

WALTER T. GODDARD.
